DeWitt Ross & Stevens S.C.(57) **CLAIM**

The ornamental design for a hair dryer attachment, as shown and described.

DESCRIPTION

FIG. 1 is a front perspective view of a hair dryer attachment; FIG. 2 is a rear perspective view thereof;

FIG. 3 is a right side view thereof, the left side view being a mirror image of the right side view;

FIG. 4 is a bottom front perspective view thereof;

FIG. 5 is a bottom view thereof;

FIG. 6 is a top view thereof; and,

FIG. 7 is an additional bottom front perspective view thereof.

The broken lines are included for the purpose of illustrating portions of the article and form no part of the claimed design.
